UNITED STATES PATENT OFFICE.

CHARLES F. SMITH, OF CHICAGO, ILLINOIS, ASSIGNOR OF ONE-HALF TO CHARLES E. SIMPSON, OF CHICAGO, ILLINOIS.

DESIGN FOR A BUTTON, BADGE, OR SIMILAR ARTICLE.

51,662.

Specification for Design.

Patented Jan. 1, 1918.

Application filed May 21, 1917. Serial No. 170,067. Term of patent 3½ years.

To all whom it may concern:

Be it known that I, CHARLES F. SMITH, a citizen of the United States, residing at Chicago, in the county of Cook and State of Illinois, have invented a new, original, and ornamental Design for a Button, Badge, or Similar Article, of which the following is a specification, reference being had to the accompanying drawings, forming a part thereof.

My improved design consists of a four leaf clover having thereon representations of the flags of the United States, Great Britain, France and Russia.

The figure is a plan view of a button illustrating my new design.

I claim:

The ornamental design for a button, badge or similar article as shown.

In witness whereof, I hereunto subscribe my name this 18th day of May, A. D. 1917.

CHARLES F. SMITH.
